UNITED STATES PATENT OFFICE.

WILLIAM H. MILLER, OF BROOKLYN, NEW YORK.

DESIGN FOR A HAMMOCK.

SPECIFICATION forming part of Design No. 25,736, dated June 30, 1896.

Application filed January 14, 1896. Serial No. 575,538. Term of patent 7 years.

To all whom it may concern:

Be it known that I, WILLIAM H. MILLER, a citizen of the United States, and a resident of Brooklyn, in the county of Kings and State 5 of New York, have invented and produced a new and original Design for Hammocks, of which the following is a specification, reference being had to the accompanying drawing, which forms a part thereof, said drawing 10 being a perspective view of a hammock in the suspended position, and which shows my new and original design.

The leading feature of my design consists in the body portion A of the hammock, the 15 elongated central portion of which is composed of a network of textile material, or of fine threads or cords, which are interwoven or bound together in meshes of regular size and form, and said body portion being provided 20 with end bars or rods B and the straight-hanging side-fringe or fringes C, the body portion of which also consists of a network of similar threads or cords, which are interlaced or bound together, and the edges of said fringe 25 or fringes being provided with depending tassels D.

Secured to or formed on the side of the hammock is a supplemental fringe, which overlaps or overhangs the fringe C and which 30 is composed of a plurality of cords or thrums, which are secured to the side of the hammock and brought together, as shown at E, and the ends thereof being united or knotted, as

shown at F, from which depend tassels G, said cords or thrums being formed into convolutions or loops, between each of which is suspended a ring H, with which is connected a tassel K, and the center convolution or loop being provided with a ring L, which takes the place of the knots E and tassels F, with 35 which the others are provided.

The entire design is such as to produce a pleasing and attractive appearance, the form of the supplemental or outer fringe being such as to give a scalloped or undulating 40 appearance thereto, and it, together with the tassels connected therewith and the rings and tassels between the separate scallops or undulations, being calculated in connection with the main fringe to harmonize and give the 45 entire design a substantial as well as an ornamental and pleasing appearance.

Having fully described my new and original design for hammocks, I claim and desire to secure by Letters Patent— 50

The design for a hammock as herein shown and described.

In testimony that I claim the foregoing as my invention I have hereunto signed my name, in presence of two witnesses, this 24th 55 day of December, 1895.

WILLIAM H. MILLER.
